Primary Examiner — Kelley Donnelly(74) *Attorney, Agent, or Firm* — Albert Bordas, P.A.(57) **CLAIM**

The ornamental design for a single sided merchandiser, as shown and described.

DESCRIPTION

FIG. 1 is a top plan view of a single sided merchandiser;

FIG. 2 is a front elevational view thereof;

FIG. 3 is a bottom plan view thereof;

FIG. 4 is a left-side elevational view thereof;

FIG. 5 is a rear elevational view thereof;

FIG. 6 is a right-side elevational view thereof;

FIG. 7 is a front isometric view thereof;

FIG. 8 is a front isometric view thereof, showing its front door open and removable bins mounted therein; and,
FIG. 9 is a front isometric view thereof, showing its front door open, and the removable bins seen in FIG. 8 set aside.
The broken lines are for environmental purposes only and form no part of the claimed design.

The claimed single sided merchandiser is used to display products.
